UNITED STATES PATENT OFFICE.

ADONIRAM J. STEWART, OF CHILlicothe, Missouri.

BUCKLE.

SPECIFICATION forming part of Letters Patent No. 391,764, dated October 23, 1888.

Application filed March 16, 1888. Serial No. 267,353. (No model.)

To all whom it may concern:

Be it known that I, ADONIRAM J. STEWART, a citizen of the United States, residing at Chillicothe, in the county of Livingston and State 5 of Missouri, have invented certain new and useful Improvements in Buckles for Siches and Harness; and I do hereby declare the following to be a full, clear, and exact description of the invention, such as will enable others skilled in the art to which it appertains to 10 make and use the same.

My invention has for its object to provide a new and simplified construction in sich or girth buckles for saddles and buckles for harness; and it consists in so constructing the same as to enable a sich or girth or hame- 15 strap, breast-strap, or other similar strap to be fastened and tightened quickly; and for saddles it is especially adapted for use in connection with the styles of saddles known as 20 "Mexican," "Western," "Cowboy," and "Cavalry."

Referring to the accompanying drawings, in which corresponding parts are designated 25 by similar letters, Figure 1 is a perspective view of my invention as applied to girth, and Fig. 2 is a longitudinal section of the buckle in detail.

The buckle A has a tongue, a, which extends 30 backward and downward from the cross-bar a', thus forming a loop or hook, a'', behind the said cross-bar and causing it as it extends from one side of the fastener to the other and forms its rear end to act as a pivot for the 35 tongue, while two bars, a³ and a⁴, extend across the fastener parallel to each other, the latter bar forming its forward edge, which is raised the thickness of the strap above the sides of the buckle. The tongue has its forward 40 end flattened on its under side in order to give a larger bearing-surface between it and the bar a³, upon which it rests when it is closed. From this peculiar form of the tongue, whenever oppositely-acting forces are applied 45 to the cross-bars a³ and a⁴ and the loop a'', the latter, being below the pivotal point, will be drawn backward and upward, thus pressing the flattened portion upon the forward under surface of the tongue against the bar a³ and 50 securely closing the buckle. A strap, B, having a ring, C, attached to one end thereof, ex-

tends between the cross-bars a³ and a⁴, doubles on itself and passes through the ring C, doubles on itself and passes between the cross-bars a' and a³, and again doubles on itself, the end 55 opposite to the ring having perforations b, through which the tongue a projects.

A pad, D, is attached to the buckle A upon the under surface thereof, and has a perforation, d, therein to permit the passage of the 60 loop of the tongue, and prevents the fastener from rubbing against the horse and thus annoying him. A ring, F, passes over the tongue and is received on the loop a'' and is secured to one end of the strap or sich above de- 65 scribed, while the ring C is fastened to the saddle on the other side.

It is evident that if the strap B is drawn tight and the tongue passed through one of the perforations b, the strain will be in two 70 directions, the rings C and F pulling opposite to each other. The loop a'' will thus be pulled backward and upward, causing the forward end of the tongue to press firmly upon the bar a³, and thus effectually preventing the strap 75 from slipping off the tongue. It is also evident that my buckle may be used for other purposes, and I do not confine myself to using it for fastening saddles.

Having now described my invention, what I 80 claim, and desire to secure by Letters Patent, is—

1. In a girth and harness buckle, a cross-bar, a', a tongue pivoted thereto and extending backward and downward therefrom, forming a loop or hook, a'', and bars a³ and a⁴ across the forward end of the buckle, substantially as and for the purpose described. 85

2. A girth and harness buckle having a cross-bar, a, a tongue pivoted thereto and extending backward and downward therefrom, forming a loop or hook, the forward end of the said tongue being flattened on one side, and parallel bars a³ and a⁴ in front of the said tongue, substantially as and for the purpose 95 described. 90

In testimony whereof I have affixed my signature in presence of two witnesses.

ADONIRAM J. STEWART.

Witnesses:

I. N. PAGE,
BEN A. RUPP.
